INVENTOR.

UNITED STATES PATENT OFFICE.

ROBERT GAIR, OF NEW YORK, N. Y.

DESIGN FOR A DOILY.

40,277.

Specification for Design. Patented Sept. 28, 1909.

Application filed July 1, 1909. Serial No. 505,523. Term of patent 3½ years.

To all whom it may concern:

Be it known that I, ROBERT GAIR, a citizen of the United States, residing at New York, borough of Brooklyn, county of Kings, State of New York, have invented a new, original, and ornamental Design for Doilies, of which the following is a full, clear, and exact specification.

In the accompanying drawing, the figure is a plan view of a doily showing my design.

I claim,
The ornamental design for a doily, as shown.

ROBERT GAIR.
